ELECTRICAL SWITCHING CONSOLE

Vincent F. Santulli, Manhasset, and Paul V. De Luca,
Port Washington, N.Y., assignors to Porta Systems
Corp., Roslyn, N.Y.

Filed June 12, 1972, Ser. No. 262,138

Term of patent 14 years

Int. Cl. D14—03

U.S. Cl. D26—14 A

FIG. 2

FIG. 1

FIG. 3

FIG. 4

FIG. 5

FIG. 1 is a perspective view of an electrical switching console embodying my new design;

FIG. 2 is a front view thereof;

FIG. 3 is a top plan view thereof;

FIG. 4 is a right side view thereof; and

FIG. 5 is a rear view thereof.

We claim:

The ornamental design for an electrical switching console, substantially as shown.
